UNITED STATES PATENT OFFICE.

NORRIS B. GREGG, JR., OF ST. LOUIS, MISSOURI.

APPARATUS FOR FORMING FUEL CHARGES FOR INTERNAL-COMBUSTION ENGINES.

Application filed October 13, 1919. Serial No. 330,189.

To all whom it may concern:

Be it known that I, NORRIS B. GREGG, Jr., a citizen of the United States, and a resident of the city of St. Louis, State of Missouri, 5 have invented new and useful Improvements in Apparatus for Forming Fuel Charges for Internal-Combustion Engines, of which the following is a specification.

This invention pertains to internal combustion engines, and resides particularly in 10 a new method of forming fuel charges for such devices, and in an arrangement of apparatus whereby such method may be practiced, and whereby fuel charges having an 15 increased effectiveness may be formed for use in an internal combustion engine.

One object of the invention is the provision of a method of forming an explosive fuel charge in gaseous or vapor form, which 20 may be employed in internal combustion engines of various types and forms, and which charge will possess such superior effectiveness as to materially reduce the amount of fuel necessary for a given amount of work.

25 A further object of the invention is the provision of such a method of forming fuel charges which may be practiced without requiring radical modifications of internal combustion engine equipment of types generally in use.

30 A further object of the invention is to provide a method of forming fuel charges which will be effective to maintain practical uniformity in the charges formed, and at the same time be susceptible of suitable variation to secure the desired variations in charges to meet different conditions.

Another object of the invention is the provision of a method of forming fuel charges 40 whereby energy of the fuel now lost in the exhaustion of the hot burned gases is conserved by utilization thereof to form a more effective fuel charge.

More specifically stated, an object of the 45 invention is the provision of a method of forming fuel charges by the combination of a hydrocarbon and air mixture with superheated steam at a suitable temperature to produce an explosive charge for an internal combustion engine having an effectiveness much greater than that of the hydrocarbon and air mixtures now commonly employed.

Another object of the invention is the provision of an apparatus whereby fuel charges 50 having greatly increased effectiveness may

be formed for and in conjunction with the operation of an internal combustion engine, and supplied to the engine to accomplish the operation thereof.

A further object of the invention is the 60 provision of an apparatus by operation of which the several objects hereinbefore specified may be attained.

Other and further objects of my invention will be pointed out hereinafter by reference to the accompanying drawings forming a part of the specification, or will be indicated in the appended claims, or will be obvious upon an understanding of the illustrative disclosure of the invention herein 70 contained; it being understood that the disclosure herein made is simply for the purpose of illustration, and is not definitive of the great variety of ways in which the method may be practiced, or the great range 75 of practical forms in which the apparatus may be embodied.

Described generally, the invention resides in the production of superheated steam either independently of the engine which is 80 to utilize the charge, or by utilization of the heat of exhausted gases from the engine, and combining steam so formed, at a temperature at or above 600° F. with proper proportions of a hydrocarbon fuel and air 85 to produce a new fuel charge in gaseous or vaporous form, and supplying such charge to the engine.

Described generally, an apparatus in which my invention may be embodied includes a chamber, in which superheated steam may be combined with air and a hydrocarbon fuel, which chamber is arranged to be supplied with air and a hydrocarbon fuel from a suitable source, either separately 90 or mixed, and with steam from a heat exchange unit,—preferably disposed in the passage for exhaust gases from the engine,—for accomplishing the production of steam. The apparatus may include also a compression device for supplying water to the heat exchange unit, and a compression device for supplying the air and hydrocarbon fuel to the chamber against the steam pressure. The practice of the method and an arrangement of the apparatus may be more definitely understood by reference to the accompanying drawing, which shows diagrammatically an internal combustion engine in sectional elevation with the charge 100 105 110

2 forming apparatus partly in section and partly in elevation.

Consulting the drawing by means of the reference characters applied, let it be understood that the character 1 designates generally an internal combustion engine which may be of single or multi-cylinder type, and which includes one or more combustion chambers 2 controlled by one or more inlet 10 valves 4 and one or more exhaust valves 5.

An inlet port 6 associated with the inlet valve provides a way through which fuel charges may be supplied to the valve 4 for admission to the combustion chamber 2, and 15 an exhaust port 7 associated with the exhaust valve provides a way of exit for exhaust gases from the combustion chamber.

In the case of a multicylinder engine, the ports 6 may be supplied from a manifold, 20 and the ports 7 may discharge into an exhaust manifold. Associated with the supply port 6, or all of them, is a mixing chamber 8, and associated with the port 7, or all of them, is a heat exchange chamber 9. The

25 walls of the heat exchange chamber 9 form a casing or enclosure for the heat exchange unit 11, which may be in the form of a coil, or a similar arrangement designed to provide a sufficient heat distribution surface. 30 This heat exchange unit is designed to accommodate free flow of fluid through it, and is of proper construction to sustain heavy pressures. A suitable pump 15, supplied from a storage source 17, is designed to feed

35 water to the heat exchange unit 11 against the pressure therein, and a suitable check-valve 19 is disposed to prevent the backing up of pressure from the heat exchange unit 11 into the pump and its supply line. A

40 steam line 21 which is designed to carry the requisite pressure is disposed to conduct steam from the heat exchange unit 11 to the mixing chamber 8, and a suitable throttle valve 25 is operable to secure desired variation in or regulation of the supply of steam to the mixing chamber.

45 A carbureting device suitable to produce a vaporous admixture of air and hydrocarbon fuel may be provided and may be of any of various effective forms of such devices now known in the art. Such carbureting device is diagrammatically illustrated at 50 10, and is arranged for the reception of hydrocarbon fuel from a suitable storage source 12, and of air through the intake 14. In operation the carbureting device 10 is designed to secure a vaporous admixture of hydrocarbon fuel and air in desired proportions determinable by adjustment of the 55 means for regulating the feed of fuel and of air. The feeding and commingling of the liquid fuel and air is induced through a gas conduit 16 by means of a suitable suction device or pump 18. This pump is effective to 60 supply the hydrocarbon-air mixture into a

chamber 8 under pressure, said supply being under the control of a suitable throttle 20.

The backing up of pressure from the chamber 8 against the pump and into its supply lines is prevented by a suitable check valve 70

22. The design of the mixing chamber 8 is such as to secure an intimate contact and commingling of the superheated steam and the gas mixture introduced thereto, and to maintain the same under pressure. It 75

may be provided with a suitable sump 24, whereby liquid products produced by the combination of superheated steam and gas mixture may be collected and discharged from the mixing chamber. The heat exchange chamber 9 likewise may be provided with a suitable sump 23 for the collection and discharge of any water condensed on the heat exchange unit 11. The pump 18 is bypassed by a branch 26 which is controlled by a valve 28, and through which branch the gas mixture may be conducted directly from the gas line 16 to the chamber 8 without going through the pump.

80 In operation, the engine may be started in the customary fashion in which internal combustion engines are started, the valve 28 being open and the rotation of the crank shaft accomplishing the operation of the piston to draw an explosive charge into the 85 combustion chamber, compress it therein, and accomplish its firing through the customary ignition mechanism. During such

operation the adjustment of the valve 25 may be such as to prevent admission of fluid 100 into the chamber 8 from the line 21. The exhaust gas discharged from the cylinders into the chamber 9 is effective upon the heat exchange unit 11 to flash the water therein

105 into steam and superheat it to a degree sufficient to maintain its temperature in excess of 600° F. after combination with the fuel mixture. This condition having been arrived at, and determined by suitable inspection or indicating means, such as the test cock 110

27, the valve 28 may be closed and the valve 25 opened so that the steam and the fuel mixture may be supplied to the chamber 8 under pressure of the pumps 15 and 18 respectively, in proper proportions determinable by adjustment of the valves 20 and 25.

115 In the chamber 8 the steam and fuel combine to form a fuel charge, the original temperature of the steam having been sufficiently great to maintain the temperature of the steam at a proper degree to accomplish its combining with the fuel mixture at a temperature in excess of 600° F. The conjunction of the steam and hydrocarbon gas mixture at this temperature enables a combination of their contained elements which is

120 productive of an explosive charge having a hydrogen content far in excess of that of the original hydrocarbon and air mixture, and which therefore is of increased combustibil-

125 ity.

130

ity and effectiveness in the production of power when utilized in the engine.

The charge so formed is of greatly increased combustibility and it therefore permits a material reduction in the amount of fuel requisite for production of any given quantity of power.

It is to be understood, of course, that the accompanying illustration of apparatus is entirely diagrammatic and it is not intended to be indicative of the requisite size or particular arrangement of parts which may be selected as the most practical or effective. It is to be understood, moreover, that my invention is not limited to the production of the superheated steam by the utilization of the waste heat in the products of combustion of the fuel, but that the steam may be produced or superheated in other fashions. Nor is it to be understood that the invention is limited to any particular means or place for the admixture of the various components entering into the fuel charge, as such, obviously, may vary with different types of engines and different kinds of fuel.

The appended claims particularly pointing out the method constituting my invention will be understood, therefore, as comprehending its practice by means of any and all suitable apparatus and materials, and those specifying the apparatus are to be understood as comprehending all species and varieties of arrangements of means effective to accomplish the result hereinbefore described.

Having thus described my invention, what I claim is:

1. In an apparatus for forming fuel charges for internal combustion engines, the combination of a source of hydrocarbon fuel supply, means for generating superheated steam under pressure, a chamber arranged for the reception of fluid from said source and said means, means for in-

ducing pressure upon fluid supplied from said source to said chamber, and means for regulating the supply of steam under pressure from said first mentioned means.

2. An apparatus for forming fuel charges for internal combustion engines, the combination of an apparatus for forming a hydrocarbon gas, a heat exchange unit for the production of superheated steam under pressure, a receptacle arranged for the reception of gas from said apparatus and steam from said unit, means for regulating the supply of fluid to and from said apparatus, and means for regulating the supply of fluid to and from said heat exchange unit.

3. The combination with an internal combustion engine of a heat exchange unit disposed in an exhaust passage of said engine, means for supplying fluid to said heat exchange unit, a chamber arranged for the reception of steam from said heat exchange unit under pressure, means for supplying a fuel gas under pressure to said chamber, and means for conducting fluid from said chamber to the explosion chamber of the engine.

4. In combination with an internal combustion engine, a source of fuel supply, a source of water supply, a heat exchange unit supplied from said last mentioned source and arranged for the generation of superheated steam under pressure, and means for supplying fuel from the source of fuel supply and superheated steam from the heat exchange unit to the combustion chamber of the engine under pressure.

5. In a hydrocarbon engine, the combination of a supply of hydrocarbon fuel, means for supplying said fuel to a mixing chamber under pressure, means for generating superheated steam, and means for supplying the superheated steam under pressure to the same mixing chamber.

NORRIS B. GREGG, JR.
